(57) **CLAIM**

The ornamental design for an abrasive stone, as shown and described.

DESCRIPTION

FIG. 1 is a left side elevational view of an abrasive stone, showing my new design, wherein the right side elevational view is a mirror image thereof;

FIG. 2 is a front elevational view of the abrasive stone, wherein the rear elevational view is a mirror image thereof;

FIG. 3 is a bottom plan view of the abrasive stone; and,

FIG. 4 is a top plan view of the abrasive stone.
